UNITED STATES PATENT OFFICE

ARTHUR TEMPLETON HUNTER, OF WEBSTER GROVES, MISSOURI, ASSIGNOR TO INTERNATIONAL COMBUSTION ENGINEERING CORPORATION, OF NEW YORK, N. Y., A CORPORATION OF DELAWARE

FURNACE WATER WALL AND WALL ELEMENT

Application filed December 16, 1926. Serial No. 155,197.

This invention comprises a novel furnace water wall, and wall element, and has more particular reference to water or similar fluid circulation walls for boiler furnaces, although available for other furnaces, the water wall being adapted to function for the generation of steam or for the superheating of steam or for purposes of keeping relatively cool a furnace wall by preventing overheating from high rate of combustion.

The general object of the present invention is to afford a furnace water wall of superior efficiency, strength and durability. A further object is to afford tubular elements by which such a wall can be built up, which elements will present an effective face toward the combustion space and possess such structure as to bring about the transfer or flow of heat at a high rate from all parts of the wall face inwardly to the tubular portion of the element and the water or other medium circulating therein. A further object is to afford a structure or cross section of water wall element which can be practically and economically manufactured, and to afford a method of manufacture thereof. Other and further objects and advantages of the present invention will be elucidated in the hereinafter following description of one or more embodiments thereof or will be understood to those skilled in the subject.

In referring to a furnace wall or water wall herein the word "wall" is intended to include any bounding surface of the furnace or combustion chamber, including a bottom wall or floor. In using the word "water" in connection with the water wall or boiler, it is intended to include water either in liquid form or vapor, since steam possesses the capacity to absorb and carry away heat through the passages of the wall elements. By a water wall element it is intended to refer to any elongated tubular element enclosing a circulation passage and provided with the characteristic features of this invention. The tube portion hereof is preferably cylindrical, with a circular interior passage, but may be of other shape.

The furnace water wall element hereof may be broadly described as comprising the tube

portion and an exterior extension which constitutes a facing and which has such ample cross section as to afford a high rate of heat transfer from all parts of the front face of the extension inwardly to the tube portion of the element and the water or other medium circulating therein.

The term "facing" is intended to include a front or inward enlargement of the tube constituting an extension or appendage which faces toward the combustion or flames within the furnace, while the "face" of the element is the front surface of such facing or extension, facing the flames.

A system or bank of wall elements such as referred to may be assembled to form a furnace water wall which itself is novel and constitutes a portion of the present invention.

Prior to the present invention, I have known of no practical method of manufacturing such a wall element or water wall as herein described and the method as hereinafter explained constitutes another portion of the present invention, the method however having been divided out and made the subject of divisional application Serial No. 307,984, filed September 24, 1928, for Method of forming an extension upon a tube.

In the accompanying drawings Fig. 1 is a transverse section of a water wall element or tube constituting an illustrative embodiment of the present invention.

Fig. 2 is a similar view showing one of many possible variations of form and structure of the wall element hereof.

Fig. 3 is a perspective view showing the preferred longitudinal structure of a water wall element having a cross section such as Fig. 1.

Fig. 4 is a front or face view of a water wall built up of wall elements such as shown in Fig. 3.

Fig. 5 is a transverse section taken on the line 5—5 of Fig. 4 indicating how the furnace wall may be closed and completed by means of suitable refractory packing and exterior shell.

Fig. 6 shows a cross section of a method and apparatus for manufacturing the novel wall element of this invention.

Fig. 7 is a diagrammatic partial enlarged view of the operations taking place in the apparatus of Fig. 6.

Fig. 8 is a top plan view of an apparatus such as is shown in Fig. 6, arranged for producing a wall element having a longitudinal structure such as indicated in Fig. 3.

The tubular wall element 10 is shown as a whole in cross section in Fig. 1 and consists of the tube portion 11 containing the water passage 12 and the exterior extension or facing 13. The latter may be described as consisting of a central part or body 14 and preferably symmetrical opposite wings 15 rendering the facing substantially wider than the diameter of the tube 11, and the front face or surface 16 extending over the whole width of the body and wings.

As will be described, the metal constituting the tube 11 is preferably integral with that constituting the extension or facing 13, but as the two consist preferably of different or united metals the drawing indicates a theoretical division line, or line of union 17 between the two. In structure the described element is preferably made from a preformed steel tube 11 and an integrally united or fuse welded cast iron extension 13. The tube may be a seamless wrought steel tube of standard type used for boiler tubes, while the extension may consist of gray cast iron cast directly and integrally upon the steel tube as will be subsequently described.

It will be noticed that the extension or facing 13 has ample cross section so as to afford a high and rapid rate of heat transfer from all parts of the face inwardly to the tube portion and the water flowing therein. This is due to the indicated shape and arrangement including a cross section of extension which is not merely thick enough to present a wide avenue of heat travel, but is of gradually widening character from the most remote point or the tips of the wings 15 to the place of heat conduction through the original tube line to the circulating water. Units of heat entering at various parts of the face are not impeded by congestion at any point of small cross section, so that at each point of the face the heat is able to travel inwardly or from the face, with substantially separate paths of travel of the heat entering at each unit of face area. This allows for practically unrestricted heat travel from the furnace wall face exposed to the fire in an inward direction towards the circulating medium. While the design might be varied, that shown in Fig. 1 is substantially able to transfer the heat from the face to the tube as rapidly as the circulating water is able to take up and carry away the heat. The described wall element is therefore self protecting from destruction by congestion and overheating at any point there-

in, a difficulty very pronounced with other forms of water wall with which I am familiar. The tube portion is protected from deterioration, while its capacity to receive heat is increased by the large exposure of the extension; and the extension is protected by the rapid conduction of received heat to the tube and its removal by circulation.

The desired conduction and results would not be attainable for extreme conditions of boiler service unless the tube portion and facing extension are unitarily connected as stated. The line or union 17 therefore preferably indicates a line of intimate and absolute contact between the two portions, with molecules or crystals interlocked continuously along the contiguous portions of the tube and facing. All the drawbacks of clamping or bolting devices are obviated, and the improvement is superior to a shrunk attachment in that the latter has but poor conduction to the tube, and by growth gradually loosens, overheats and burns away.

Some of the preferable features of the illustrated wall element are as follows. The face or front surface 16 is preferably plane and flat so as to lie in the plane of the water wall, and with adjacent wall elements afford a substantially flush, flat wall. Preferably also the middle portion 14 of the extension is of substantial thickness so that the original tube periphery does not directly contact the flames, although in some cases the thickness of the facing extension might be reduced to leave the tube portion substantially centrally exposed. The entire extension 13 preferably spans a substantial extent of periphery of the tube, more than 90° but less than 180°, as shown. One factor is to avoid excessive weight and this is well accomplished by the particular curved contour at the outer sides of the wings 15 as shown in Fig. 1. The facing extension also is preferably bilateral and symmetrical, thus minimizing the distance of travel of the heat from the extreme wing tips to the circulating tube for any given spacing of the tubes in the wall. The design shown minimizes any tendency to bend or warp the tube by expansion or growth.

The advantageous heat conduction of the invention is approximately indicated by the heat travel arrows 18 shown at the left side of Fig. 1, showing that at each point in the facing the heat received from the flames travels inwardly and not along or parallel to the face; and the successive approximate transverse lines 19 indicate that the path or avenue of heat travel progressively widens from the most extreme points to the water circulation passage.

The modification shown in Fig. 2 embodies a tube portion 11^a similar to Fig. 1 and a facing extension 13^a of similar but modified contour and having embedded in the face

thereof plates or blocks 21 of some highly refractory material having high heat conducting qualities, such as carboglaze, a form of silicon carbide, alundum, or the like. This 5 structure increases the life of the wall due to the greater resistance to heat of the refractory as compared with cast iron.

Rather than apply the extension facing 10 continuously to the tube portion it is preferably applied in relatively short sections as 15 shown at 13, 13 in Fig. 3, with spaces or grooves 23 between each two sections. These spaces facilitate the manufacture of the wall 20 element and in use they allow expansion of the hot sections without causing curving of the element and swelling of the wall. The arrangement also allows for the gradual 25 growth which occurs with repeated heatings of ferrous metals. While a mild steel, low in carbon, is preferable for the preformed tube, cast iron is superior for the facing, for example a gray iron high in carbon, and the rapid transfer of heat enables the iron to be kept from excessive temperatures, and if kept 30 below 900° F. this may preclude the growth occurring at higher temperatures.

Taking a specific instance, namely, with a #9 seamless boiler tube, having a diameter of about 3 inches, the spaces between the 35 sections 13, 13 may be $\frac{1}{4}$ inch. Each section may be about 6 inches long and of a width slightly less than the spacing between the tubes. Fig. 4 shows a furnace wall constructed in this manner from elements such 40 as shown in Fig. 3. The center lines of the elements having a 6 inch spacing, each section 13 may be $5\frac{7}{8}$ inch wide, thus allowing a separating space 25 of $\frac{1}{8}$ inch between the successive elements for expansion.

45 It will be understood that the wall tubes may have their ends expanded into headers as is usual with circulation tubes in boilers and furnaces. The tubes, for example, may be vertically arranged and of 20 foot length, in which case the facing extensions may be omitted above the highest level of the combustion flames in the furnace. If needed to conform to the arrangement of the boiler or furnace the wall elements of this invention 50 may have a curved or bent shape, preferably applied to the tubes before the addition of the extensions.

The illustrated wall structure with the given dimensions is relatively light in weight 55 and may weigh as low as 25 pounds to the square foot, thus being economical of metal and more readily handled in constructing a furnace.

The water wall indicated in skeleton in 60 Fig. 4 may be completed by inserting a suitable packing between and behind the facing extensions or sections 13 of the wall. Thus in Fig. 5 a packing 27 is shown. This may be both refractory and non-conducting in 65 character, such as asbestos paste, and the

packing may be confined in the manner shown by an outer sheet metal casing or shell 28. A mode of interconnection for spacing the water wall from the exterior shell is indicated in the form of clamps or braces 29 70 shown extending more than half way around the tube portion 11 of some of the wall elements, where the same are suitably tightened, while the outer extension or stem of each clamp device is secured by nuts or otherwise in proper relation to the enclosing shell 28. Fig. 5 therefore indicates a completed water wall embodying the present invention.

Another advantage of the water wall of 75 this invention is that fuel of a flowing nature may be injected into the furnace between the sections of the wall. Thus in Figs. 4 and 5 is indicated a tube or burner 30 projecting through the furnace wall and directing a stream of fuel, which may be pulverized fuel 80 mixed with air, or oil, the edges of the wall sections at the injecting point being broken away to accommodate the burner. A furnace so constructed is very effective for pulverized coal combustion.

Indeed, the wall may be open for the 85 through passage of products of combustion or settling of ashes, in which case the spaces between the tube elements of the wall will be unpacked, and may be enlarged by reducing the lateral width or dimension of each 90 facing or extension, so long as it faces the fire, protects the tube and carries the radiant heat effectively to the circulating water, with ample section to avoid congestion of heat; 95 an example being the lower tier of tubes of a water tube boiler, which may carry facing extensions at their lower sides or facing the flames, in which case the gaps or grooves 100 23 are not necessary as there is no continuous flush surface to be distorted by swelling.

The water wall element, hereinabove 105 described, may be manufactured on an economical basis by the following method. Starting with a standard seamless steel tube of 110 the desired shape and length this should first be thoroughly cleaned prior to the casting operations. It should first be dipped in pickling acid to loosen the scale, for at least half of the circumference of the tube, and this should be followed by sand blasting 115 until the surface is bright and clean.

A portion of the length of the tube may then be inserted in a special mold such as is indicated in Fig. 6. This comprises a 120 lower mold section 32 and above it a removable upper section or cope 33. The casting space 34 corresponds with the cross section shape of the facing extension 13 as seen in Fig. 1, and is to be formed by a suitable 125 pattern positioned against the side of the tube 11 during the molding of the sand. A sheet gate or wide channel 35 is indicated for conducting the molten iron to the lower part of the casting recess 34, and a pouring spout 130

36 is arranged to connect with the gate. The sand in the cope 33 may be supported and held by gagets 37 or other devices known to the molding art. For reasons that will appear it is preferable to arrange an exit or riser 38 for the molten iron, so that it can be poured into the mold in excess and run out through the riser and thence overflow through a gutter 39. The molten metal will be able to fill the casting space 34 to the highest point thereof due to the porosity of the sand, and the riser 38 preferably takes off from the recess 34 at a point as close as possible to the upper side of the preformed tube 11. In some cases a permanent mold might be used in lieu of the sand mold described.

The arrangement thus described may be employed for casting a single extension section 13 upon the steel tube, or by the arrangement shown in Fig. 8 may be employed for simultaneous formation of a number of such sections. The order of production of extension sections may be varied. Thus alternate sections may be cast upon the tube and subsequently others between them; or a series of sections may be cast and after the casting is cooled the tube may be shifted along for the production of another series and so on until the full desired number of sections is cast. In Fig. 4 the pouring spout 36 is shown as having multiple or divided channels 41 entering the respective sheet gates 35 for the several sections; and likewise the several risers 38 are shown delivering through separate overflow channels 42 to a common overflow point. The several casting recesses 34 may be originally formed as a single recess and spaced before casting by a series of baked cores 43 arranged between the successive sections and representing the spaces 23 shown in Fig. 3.

According to the present method the preformed tube is preferably preheated to a fairly high degree for example 800° to 900° F. so as to soften the metal or prepare it for the fuse welding operation by which the facing extensions are rendered integral with the tube. For the purpose of such preheating a burner or torch 45 is indicated and this may be used to drive through the tube flames from the combustion of oil or gas. Uniformity or preheating is desirable and I have devised an arrangement for electrically preheating the tube for this purpose. When the blow torch is used it is preferably operated alternately from one end and then the other end of the tube so as to bring the tube temperature as high and as uniformly as possible over the entire length or portion to be treated.

The casting, it will be observed, is performed directly upon the surface of the preheated tube 11. The molten cast iron may be at a temperature of about 2900° F. Accord-

ing to this invention the preferred operation is to allow the molten iron to fill the casting recess, and then, while part of the iron flows out through the riser, keeping up a continuous flow through the gate 35, recess 34 and the riser 38, for a substantial period in order to elevate further the temperature of the steel tube, bringing it nearer to the fusion point and insuring integral uniting of the tube and extension, with molecular interlocking of the two portions of the finished product.

The diagram Fig. 7 indicates substantially the operation. The casting space 34 is full of molten iron. The sheet gate 35 brings the iron into the recess across the whole width thereof, while the sheet riser 38 is also of the full width, this arrangement insuring the continuous passage of a full width stream of molten iron through the recess 34 from the entrance to the exit, this stream represented by arrows 47 on the diagram. It will be noticed that the natural path of the molten iron stream is toward the surface of the steel tube and thence around such surface to the riser 38. The molten iron will be at its hottest temperature near the lower part of the tube but will maintain a substantially uniform heating effect because the arrangement causes the stream to travel in more intimate contact with the tube as it progresses and while it is cooling.

The result is that the entire exposed and preheated surface of the tube is elevated to a fairly even temperature for integral uniting or fuse welding with the cast iron extension formed upon it. It is estimated that the tube steel, at its exposed surface, will in this process be raised nearly to, but not over 1250° to 1300° F., at which it will soften enough for welding or fusion to the cast metal, without actually melting or running.

The preferred manipulation is substantially as follows. The molten iron is poured from a ladle into the spout 36 first at a fast rate of flow in order to fill the mold quickly. As soon as the mold is filled and overflow at the riser commences, the pouring should be slowed down to as slow rate as practicable. By this plan the maximum heating up of the tube by the iron is secured with the minimum of erosion of the steel by the stream of iron. The pouring may be continued for about one minute more or less. The extent of pouring is best determined by the weight of metal, and preferably several times the weight of the casting itself should be flowed through the mold. For example, in casting four facing sections, as in Fig. 8, and assuming that these will contain about 25 pounds of metal, a ladle may be employed which when filled to a certain point will hold 100 pounds of molten iron. The pouring will then be continued until all of the iron from the ladle has passed into or from the mold.

The spout 36 being at a higher level than the discharge channel 39 gravity will maintain the flow until the operation is completed. When all of the iron is poured the casting will be allowed to cool and harden and when subsequently removed from the mold will be found integrally attached to the steel tube. The extent of the operation of flowing the hot iron along the steel surface must be carefully determined. Excessive operation will cause the iron to wash away portions of the heated steel and so impair the strength of the tube. If the pouring is insufficiently continued the steel will not be brought to the welding temperature and there will be no real bond or effective fusion established between the metal of the tube and the extension. The result will be greatly impaired conductivity so that one of the main objects of the invention would be affected; and moreover the inadequately united portions are liable subsequently to separate. The operation should be so calculated as to bring the steel tube to a welding temperature, the iron thereby becoming welded and fused to the tube with a thorough union involving an intercrystalline structure. The formation of bubbles at the line of union is precluded by the described operation, since the bubbles tend to rise without having access to the surface of the steel tube, as indicated at 48 in Fig. 7.

Many variations suggest themselves. Thus by a suitable elongated mold an entire twenty foot tube can be treated in one operation. The tube may be of any nature suitable to its purpose, and the facing or extension is not necessarily of cast iron but may be cast steel. Other modes of effecting fusion, welding or uniting of the two portions can in some cases be substituted, for example, autogenous welding of preformed tube and extension, but it is believed that effective water walls for high temperature furnaces can be best manufactured on a practical basis by the preferred system described.

The described molding and casting method may be improved and quickened as follows. The mold portions containing the gates and risers may consist of previously prepared hard-baked dry sand cores, and the runner and pouring spout may likewise be composed of baked sand and located directly on top of the baked core members. After the tube is placed in the mold the baked cores defining the facing extension are placed against the tube, and then green sand is placed to surround the tube and cores and tamped tightly, before the pouring of the measured amount of molten iron as already described. This system reduces errors and losses, and makes all castings uniform; and accidental entry of dirt into the mold is prevented. The molding time is shortened, and the molding requires less skill. The output from each mold is in-

creased, since one set of men may be employed in making the separate baked cores, while another set is applying cores and forming the molds. The larger output is therefore accompanied by lower cost of production. The small cores separating the casting into longitudinal sections may advantageously be composed of cast iron, and they may be pasted and covered with sand before being applied at the mold; this giving a cleaner separation between sections, and giving a more uniform result as the cast iron core is not subject to crushing; and it is readily knocked out after the cooling and removal of the product.

There have thus been described a furnace water wall and a wall element and a method of making the same embodying the principles and attaining the objects of the present invention. Many matters of operation, combination, arrangement, structure and design may be variously modified without departing from the principles and therefore it is not intended to limit the invention to such matters except to the extent set forth in the appended claims.

What is claimed is:

1. In or for the wall or lining of a furnace, a unitary metallic element adapted to absorb radiant heat and to be cooled by interior circulation, the same comprising a tube portion, and an integral facing extension thereon surrounding and covering the inner side only of the tube and facing the fire but terminating to leave uncovered the outer side of the tube, and having such ample thickness of metal along the paths of heat conduction from the exposed face to the tube as to afford high conduction rate from all exposed portions to the medium circulating in the tube and thus to avoid destructive congestion of heat.

2. In or for the wall or lining of a furnace, a unitary metallic element adapted to absorb radiant heat and to be cooled by interior circulation, the same comprising a preformed tube portion, and an added facing extension integrally fused thereon and surrounding and covering the inner side only of the tube and facing the fire but terminating to leave uncovered the outer side of the tube, and having ample thickness of metal along the avenue of heat conduction from the exposed face to the tube.

3. A furnace element as in claim 2 and wherein the tube portion is a preformed steel tube, and the extension is of cast iron fused on to the tube.

4. In or for the wall or lining of a furnace, a unitary metallic element adapted to absorb radiant heat and to be cooled by interior circulation, the same comprising a tube portion, and an integral facing extension thereon surrounding and covering the inner side only of the tube and facing the fire but terminating to leave uncovered the outer side of the tube,

said extension having a sectional thickness increasing from its most remote portion to the tube to afford an enlarging avenue for conduction from the face to the median in the tube.

5. A furnace element as in claim 4 and wherein the extension has a thickness sufficient to span between 45° and 90° of the tube circumference at each side of a center line taken symmetrically to the surface of the extension facing the fire.

6. In or for the wall or lining of a furnace, a unitary metallic element adapted to absorb radiant heat and to be cooled by interior circulation, the same comprising a tube portion, and an integral facing extension thereon surrounding and covering the inner side only of the tube and facing the fire but terminating to leave uncovered the outer side of the tube, said extension having a cross sectional thickness near the tube at least several times that of the tube wall.

7. In or for the circulation-cooled wall or lining of a furnace, a tubular metallic element adapted to be exposed to radiant heat, the same comprising a tube portion, and, arranged along the length of the tube portion, a slightly separated series of facing extension sections, each surrounding and covering the inner side of the tube but terminating to leave uncovered the outer side of the tube.

In testimony whereof, I have affixed my signature hereto.

ARTHUR TEMPLETON HUNTER.
